FILTER CARTRIDGE FOR LUBRICATING
OIL CLARIFIERHarland Thomas, Port Ewen, N. Y., assignor to
Thomas Oil Cartridge, Inc., Port Ewen, N. Y.

Application June 22, 1949, Serial No. 100,610

4 Claims. (Cl. 210—138)

1

This invention relates to lubricating oil clarifying devices for installation in the oil circulating system of a motor and more particularly to the filter cartridge mounted in the clarifying device.

In most of the present filters a replaceable cartridge is formed to be readily removed from the oil clarifying device and to permit quickly mounting a new clean filter. These cartridges are generally formed with a screen at the base of a cloth bag and cotton waste is packed into this bag and the bag is tightly tied at its top. This cartridge when mounted in an oil clarifying device must be held in a compressed form so that the oil pressure will not lift the bag and by-pass the bag and defeat the purpose of the oil cartridge or bag. There are various types of mountings but as a rule the bag is mounted by its screen end against the base of the filter and a metal crown is formed to fit against the top of the bag and is compressed against the bag by a mechanical means such as a threaded element.

An object of this invention is to provide a replaceable oil cartridge for an oil clarifying unit that may be securely mounted to prevent the bypassing of oil through the clarifying device.

A further object of this invention is to provide an oil clarifying cartridge mounted within a rigid container that may be rigidly affixed within an oil clarifying device.

A further object of this invention is to provide an oil clarifying cartridge mounted within a can in which a spring having the general form of a helix is mounted over the perforated base of the can and cotton wadding is compressed about the spring to fill the can and a perforated top member secured to the top of the can to retain the wadding in a compact relationship.

A further object of this invention is to provide an oil clarifying cartridge having a rigid exterior container and provided with a perforated top and base and in which a spring having the general form of a helix is mounted within the can to provide a hollow center at the base of the cartridge and in which cotton wadding is securely packed and retained in this packed relationship within the can.

Further objects of this invention shall be apparent by reference to the following detailed description and the accompanying drawing in which the figure illustrates a perspective of the oil clarifying cartridge partially in section.

Referring to the figure there is illustrated a rigid container 10 having the general formation of a cylinder. The cylinder 10 is provided with two perforated end members, a top member 11

and a base member 12. The top member 11 may be formed so that it can be removed from the cylinder 10 and may be readily affixed to the cylinder 10 by snapping the member 11 into a grooved formation or by affixing in any other manner to retain the disk 11 in a fixed relationship to the cylinder 10. In preparing the oil cartridge for use, a spring 14 which may be formed as a helix is first inserted into the can formation with the larger radius of the spring 14 resting on the base 12. A specially prepared cotton wadding that is absorbent and provides the necessary filtering characteristics is then wrapped around the periphery of this spring and the cylinder 10 is completely filled or packed with this wadding. The disk 11 is pressed and snapped into place to retain the whole unit in a compact relationship as illustrated in the figure. Thus the unit is ready for installation in an oil clarifying device.

It is apparent that with the filter 10 mounted within a clarifying unit that the used oil entering the clarifier will pass through the perforated bottom member 12 of the oil cartridge 10 and will readily flow upward through the empty helix of the spring 14 and will penetrate the cotton wadding of the cartridge passing upward through the wadding and out through the perforated top member 11. When the cartridge 10 has been used for a considerable time it is easy to remove this cartridge and replace it with a clean fresh cartridge. The cartridge 10 is provided with a finger ring 40 at its center which may be readily caught by one finger and the cartridge 10 may be pulled out of the clarifier unit and in turn a new cartridge 10 may be forced into the unit.

It is apparent that the oil cartridge unit described may be varied to fit any particular oil filter unit and similarly clamped without departing from the spirit of this invention and this invention shall be limited only by the appended claims.

What is claimed is:

1. A cartridge for use in an oil clarifier unit comprising a can shaped rigid container with a removable perforated top, a perforated bottom, a spring formed as a helix mounted in juxtaposition to the bottom of the container, a filter of cotton wadding packed into said container to rest upon said spring and completely fill said container, said spring forming an open cone shaped chamber in the bottom of said packing, said removable top securely affixed to the container to retain the filter in its compact pressed relationship within the container.

2. A filter cartridge comprising a metallic can

container having a perforated bottom and top, said top removable, a cone shaped spring mounted within the can with the apex toward the top of the can, a filtering material of cotton wadding twisted and compressed about the periphery of the spring and compressed in the can to completely fill the space above the spring in said can, the area of the lower face of said cotton wadding being greater than the area of the perforated bottom of the container, the space above the spring in said perforated top secured to said can to retain the wadding in its compressed relationship for use.

3. A cartridge for use in an oil clarifier unit comprising a cylinder shaped rigid container with a top and bottom that are perforated, a spring inserted within said container, a filtering material of cotton wadding inserted within said container over said spring, said spring abutting with the bottom of the container on one end and abutting with said cotton wadding on the opposite end to retain said filtering material away from the

perforations in the bottom of said container, said perforated top retaining said cotton wadding securely packed within said container.

4. In a device according to claim 3 in which said spring is formed generally cone shaped and rigid enough to retain this shape when the container is packed with the cotton wadding.
